FIG. 1 is a perspective view of the device of the present invention;

FIG. 2 is a front view of the device shown in FIG. 1 illustrating the device with a helically-coiled hose stored therein;

FIG. 3 is a rear view of the device shown in FIG. 1; FIG. 4 is a top view of the device shown in FIG. 1; FIG. 5 is a bottom view of the device shown in FIG. 1; and, FIG. 6 is a right side view of the device shown in FIG. 1 illustrating the device with a helically-coiled hose stored therein, the left side view being a mirror image of the right side view.

The broken lines showing environment in the drawings are for illustrative purposes only and form no part of the claimed design.
